US00D927314S

(12) **United States Design Patent** (10) **Patent No.:** **US D927,314 S**
(45) **Date of Patent:** **** Aug. 10, 2021**

(54) **DISPENSER**

(71) Applicant: **S.C. JOHNSON & SON, INC.**,
Racine, WI (US)

(72) Inventor: **Brian T. Davis**, Burlington, WI (US)

(73) Assignee: **S. C. Johnson & Son, Inc.**, Racine, WI
(US)

(57) **CLAIM**

The ornamental design for a dispenser, as shown and described.

DESCRIPTION

FIG. 1 is a front elevational view of an ornamental design for a dispenser;

FIG. 2 is a right side elevational view of the dispenser of FIG. 1; and,

FIG. 3 is a left side elevational view of the dispenser of FIG. 1.

The broken lines are included for the purpose of illustrating portions of the dispenser that form no part of the claimed design.

1 Claim, 2 Drawing Sheets
